UNITED STATES PATENT OFFICE

2,231,937

INJECTION NOZZLE FOR INTERNAL COMBUSTION ENGINES

Alfred Meyer and Walter Lippert, Stuttgart, Germany, assignors to Robert Bosch Gesellschaft mit beschränkter Haftung, Stuttgart, Germany

Application November 16, 1938, Serial No. 240,822
In Germany December 14, 1937

4 Claims. (Cl. 299—107.1)

The present invention relates to cooled injection nozzles for internal combustion engines, of the type having a nozzle body in which the end from which the fuel passes into the cylinder of the engine is so enclosed by a cooling jacket, that between the cooling jacket and the nozzle body there is formed a hollow space for the reception of a cooling liquid.

The purpose of the invention is to achieve effective cooling by simple means and, despite limited space conditions, to bring comparatively large amounts of cooling medium into the vicinity of the points to be cooled.

According to the present invention an injection nozzle for internal combustion engines is provided with a substantially cylindrical jacket surrounding its fuel outlet end, through which jacket a cooling fluid is circulated, said jacket being firmly connected with the said nozzle around the fuel outlet point and sealed at its opposite end by a suitable nut to the outside of the body of said nozzle.

The invention is more particularly described with reference to the accompanying drawing, in which:

Figure 1 is a longitudinal section through a nozzle on the line I—I in Figure 2.

Figure 2 is a cross section on the line II—II in Figure 1.

Figure 3 is a longitudinal section on the line III—III in Figure 2.

Figure 4 is a cross section on the line IV—IV in Figure 1, and

Figure 5 is a longitudinal section through a modified form of construction of a nozzle.

In the drawing:

Numerical 1 is a nozzle holder, to the end surface 2 of which a nozzle body 3 is attached. In the interior of the nozzle body 3 is disposed a nozzle needle 4, which is pressed on to a seating surface 5 by a spring. The fuel passes through a conduit 6 provided in the nozzle holder into a conduit 7 in the nozzle body 3. From here, the fuel flows through annular spaces 8, 9 towards the seating surface 5 of the nozzle and, as soon as the pressure from the injection pump (not shown) has become large enough to overcome the force of the said spring, it raises the nozzle needle 4, so that fuel is injected at 10 into the cylinder of the engine or into a primary chamber or the like.

Surrounding the orifice 10, the nozzle body 3 is firmly connected by brazing with one end of a cooling jacket 11. The other end 12 of the cooling jacket 11 is constructed as a flange which is bindingly pressed against a shoulder 14 on the

nozzle body 3 by a cap nut 13. In order to obtain efficient tightness without bending of the parts despite the heating during the soldering process, it is desirable to effect the brazing in a tightly clamped condition. Welding may be employed for connecting the parts with each other, if desired, instead of brazing.

The nozzle body 3 is reduced in diameter where it is surrounded by the cooling jacket 11 such that its cross section has substantially the shape shown in Figure 4. By means of this reduction, a hollow space 15 has been provided for the reception of a cooling liquid. In the example of construction shown, the hollow space 15 is of a horse shoe section intersected by a bar 16, which, according to Figures 3 and 4, consists of one piece with the nozzle body 3 and bears tightly on the inner wall of the cooling jacket 11. As shown in Figure 3, a conduit 17 is provided in the bar 16 which is connected between the hollow space 15 through a conduit 18 running tangentially to the direction of the nozzle, and with the feed pipe of the cooling jacket through a conduit 19 in the nozzle holder 1.

As shown in Figure 4, the conduit 18 opens on the right hand surface of the bar 16 and as shown in Figure 3, it opens below in the nozzle body 3, so that the cooling liquid supplied enters the lower part of the jacket in the direction of the arrow 20 in the immediate vicinity of the part to be cooled.

As shown in Figure 3, a conduit 21 leads from above the hollow space 15 and leads through a conduit 22 in the nozzle holder to the cooling oil return pipe (not shown). As may be seen in Figure 2 and as indicated in Figure 4, by the sign X, the conduit 21 begins on that side of the bar 16 which is opposite to the conduit 18.

The cooling medium is consequently forced to traverse the entire hollow space 15 from the lower end of the one side of the bar 16 to the upper end of the other side of the bar 16 and to cool the entire lower part of the nozzle effectively. With this arrangement, despite the small space that is available especially in vehicle engines for installing the lower nozzle parts, a comparatively large cooling medium chamber can be utilised advantageously for the cooling. Further, the cooling jacket can be manufactured cheaply as a simple part, preferably as a pressed piece. For locking the nozzle body 3 relative to the nozzle holder 1, as shown in Figures 1 and 2, a holding pin 23 is employed.

Another form of construction of the invention is shown in Figure 5. This differs from the form of construction according to Figures 1 to 4 only in that with this construction the cooling jacket 11a is employed.

is tightened by means of the conical construction of the outer jacket by an appropriate inner cone 24 in the cap nut 13a instead of the flange as used in the construction according to Figures 5 1 to 4.

We declare that what we claim is:

1. A fuel injection nozzle for internal combustion engines, including a nozzle body and a cooling jacket surrounding its fuel outlet end, in which 10 a bar or rib extends axially of, and projects radially in one direction from the nozzle body itself and bears with its outer surface on the inner wall of the cooling jacket, so as to form a seal therewith providing a single longitudinal partition 15 dividing the substantially annular hollow space between the jacket and the body, a passage for supplying cooling fluid to the said space leading through the rib or bar itself and opening into said space at a position adjacent to the fuel outlet 20 end of the nozzle body.

2. A fuel injection nozzle as claimed in claim 1, having a conduit for the return of the cooling fluid, which conduit commences at that end of the

hollow space remote from the outlet end of the nozzle body.

3. A fuel injection nozzle as claimed in claim 1, having a conduit for the return of cooling fluid from the hollow space, and in which the bar or 5 rib is formed in one piece with the nozzle body, and the outlet end of the passage for the supply of cooling fluid to the space is located on one side surface of the rib, while the inlet to the return conduit from the hollow space is located at 10 the opposite side of the bar or rib and remote from the outlet end of the supply passage.

4. A fuel injection nozzle as claimed in claim 1, in which a movable needle valve is pressed under 15 spring pressure onto a seating surface formed in the nozzle body, and in which the outlet opening for the cooling fluid supply is provided in the bar in the region of the plane of the seating surface and is directed substantially tangentially of the curvature of the nozzle body periphery. 20
